ADVERTISING INSERT HOLDER FOR SUPERMARKET CARTS

Donald H. Fosher, 352 Diplomat Lane, Chesterfield, Mo.
63017, and Robert J. Brace, 9415 Crestwood Manor
Drive, St. Louis, Mo. 63126

Filed May 17, 1973, Ser. No. 361,251

Term of patent 14 years

Int. Cl. D20—03

U.S. Cl. D96—3

FIG. 2

FIG. 1 is a perspective view partly from above and to the right, of an advertising insert holder embodying the present design. The left side is identical to the right side shown, and the rear edge is identical to the front edge shown.

FIG. 2 is a perspective view showing the advertising insert holder open.

The dashed lines depict advertising insert cards in place in the pockets of the present advertising insert holder.

We claim:

The ornamental design for an advertising insert holder for supermarket carts, substantially as shown and described.
